UNITED STATES PATENT OFFICE.

GEORGE L. McGREGOR, OF CHICAGO, ILLINOIS.

MODE OF MAKING BOILER-STAYS.

SPECIFICATION forming part of Letters Patent No. 430,672, dated June 24, 1890.

Application filed April 3, 1890. Serial No. 346,419. (No model.)

To all whom it may concern:

Be it known that I, GEORGE L. McGREGOR, a citizen of the United States, residing at Chicago, Cook county, Illinois, have invented 5
5 a new and useful Improvement in Boiler-Stays and Processes for Making the Same, of which the following is a specification.

In making boiler-stays it has heretofore been customary to first form the feet or part 10 to be attached to the head of the boiler, then to weld onto this a bar of iron forming the shank, and to weld to this bar in turn a flat piece of iron adapted to be secured to the shell of the boiler. This has rendered seven 15 heatings necessary in making every stay, and has therefore been expensive and taken considerable time. My object is to avoid these defects, and I form a stay out of a single piece of sheet-steel, without any welding whatever 20 and at a single heating; and the invention consists in the process and features and details of construction, hereinafter described and claimed.

In the drawings, Figure 1 represents a plan 25 view of the metal blank from which the stay is made; Figs. 2 and 3, similar views showing the stay partially and entirely completed, respectively; and Figs. 4, 5, and 6 are end views of Figs. 1, 2, and 3, respectively.

30 A is the metal blank; A', a slit therein; a', holes drilled therein; B B, the edges of such blank.

C C are the feet of the completed stay; D, the shank, and E the body thereof.

35 In making my improved stay I first form a blank A out of any suitable material, as steel plate, and preferably of the shape shown in Fig. 1, and drill or punch in the same four holes a a', substantially in the relative positions shown, and of a proper size to receive the rivets. In the upper end of this blank I form a slit A', its depth being equal to the length of the feet, as hereinafter described. The upper end of this blank for a suitable 40 distance—say, about to the line X X—is then heated to the proper temperature, and its

edges B B are lapped or folded together, curving gradually up from the flat portion or body of the blank. Fig. 2 represents this stage of construction, the blank being folded 50 for a portion of its length and left flat for the remainder to form the body E. The upper portions of the blank are bent—one to the right and the other to the left—substantially at right angles to the shank, forming the completed stay, as shown in Fig. 3.

In applying this device the feet C C are fastened by suitable means to the head of the boiler and the body E to its shell.

I claim—

1. The improvement in the art of manufacturing boiler-stays, which consists in forming a metal blank A with a slit A', bending up the sides of the blank throughout a portion of its length to form the shank D, and bending out the upper ends of the bent sides to form the feet, substantially as described.

2. The improvement in the art of manufacturing boiler-stays, which consists in forming a sheet-metal blank A with a slit A' and holes 65 a a', folding the blank together throughout a portion of its length, thus forming a shank D, and a flat body E, adapted to be secured to the shell of the boiler, and finally bending out the upper ends of the folded portion at 70 right angles to the shank to form feet to be secured to the boiler-head, substantially as described.

3. A boiler-stay made from a single piece of sheet metal and comprising a flat body E, 75 a shank D, and feet C C, substantially as described.

4. A boiler-stay made out of a continuous metallic blank by bending the same to form feet C C to be secured to the boiler-head, a shank D, and a flat body E, to be secured to the boiler-shell, substantially as described.

GEORGE L. McGREGOR.
